United States Patent Office.

E. C. LITTLE, L. E. CLOW, AND D. H. NATION, OF ST. LOUIS, MISSOURI.

Letters Patent No. 87,688, dated March 9, 1869.

RESERVOIR COOKING-STOVE.

The Schedule referred to in these Letters Patent and making part of the same.

To all whom it may concern:

Be it known that we, E. C. LITTLE, L. E. CLOW, and D. H. NATION, of St. Louis, in the county of St. Louis, and State of Missouri, have invented a new and useful Improvement in Cooking-Stove and Range; and we do hereby declare that the following is a full, clear, and exact description thereof, which will enable those skilled in the art to make and use the same, reference being had to the accompanying drawings, forming part of this specification.

This invention relates to improvements in cooking-stoves or ranges, whereby they are made much more useful and economical than stoves or ranges of ordinary construction; and

The invention consists in the arrangement of a water-reservoir, with reference to the exit-flue and fire-box of the stove, whereby important advantages are gained, as will be hereinafter more fully described.

Figure 1 is a vertical longitudinal section of the stove through the line *x x* of fig. 2, showing the general construction and arrangement of parts.

Figure 2 is a sectional horizontal view, looking from the line *y y* of fig. 1.

Figure 3 is a detailed view of the lower fire-flue, arranged differently from that shown in fig. 1, it being a modification of the same.

Similar letters of reference indicate corresponding parts.

A represents the main oven;

B is the fire-place or chamber;

C indicates the fire-flue, which encircles the oven A;

D represents the ash-pit; and

E is the grate in the bottom of the fire-place or chamber B.

F is a water-reservoir, which is placed immediately in front of the flue C and chamber B, and is made either portable or fixed in its place, as may be desired.

G represents the covers of the reservoir F, which are made to slide longitudinally each way from the middle, and to act independently of each other.

In this form they are extremely useful as a receptacle for dishes in the process of cooking.

The sides of the fire-chamber B may be made of corrugated plates, and they are perforated near their upper edges, as seen at *h*, so as to allow of jets of air to be discharged into the heated gases, above the fuel, by which a more perfect combustion is produced than could be obtained above a closed fire-chamber.

The door of the ash-pit D is made with a register, for admitting air and controlling the draught.

The back and bottom plates of the stove may be made curved, instead of flat, if desired, for the purpose of forcing the heat to the outer sides of the flue, or V-shaped plates or strips may be arranged in the flue, to govern the current of heat, as represented in the detailed view, fig. 3.

By this arrangement the heat would be conveyed beneath the front part of the water-reservoir.

J is the roasting-chamber, or oven, which is heated from the exit-flue C.

It will be seen that by opening the damper I, a direct draught from the fire-chamber is produced, and that the heat and products of combustion, instead of being allowed to pass around the oven A, may be diverted directly upward, so as to heat the roasting-oven.

The heat from the flue C is admitted into the roasting-chamber through a sliding damper in its back, seen at *k*.

The sides and ends of this roasting-chamber are fitted with heat-reflectors, which are made detachable and reversible, so that they may be changed, or the side reversed, when necessary.

Providing this chamber with heat-reflectors enables us to use the heat to the best possible advantage.

When the damper *k* is closed, the chamber J may be used as a baking-oven.

m is a removable grated partition in this chamber, the same as is common in ordinary baking-ovens.

N is a warming-oven, which is attached to the back part of the roasting-chamber, and which receives its heat from the same flue, C.

These chambers, or ovens J and N, are detachable from the stove, as will be seen by inspecting the drawing at the point marked *o*, and the stove may be constructed and used without them, when they are not required.

P is the top of the stove, which is provided with the usual boiler and cooking-apertures, as seen in fig. 2.

The position of the water-reservoir is such that its top is below the top of the stove, so that it is in the most convenient position for use at all times, either for filling or using the water therefrom, and as the products of combustion impinge against its bottom, and pass upward, directly back of its side, it absorbs all the heat required, without interfering in any manner with the cooking or other operations about the stove.

Provision is made in front of the stove, beneath the reservoir, for clearing the flue, as seen at *q*, fig. 1.

We claim as new, and desire to secure by Letters Patent—

The arrangement of the reservoir F, in front of and adjoining the exit-flue C, resting upon its horizontal portion, and with reference to the fire-box B, as herein described; for the purpose specified.

E. C. LITTLE.

L. E. CLOW.
